UNITED STATES PATENT OFFICE.

WILLIAM R. MILLER, OF PITTSBURG, PENNSYLVANIA, ASSIGNOR TO FORTER MILLER ENGINEERING COMPANY, OF PITTSBURG, PENNSYLVANIA, A CORPORATION OF PENNSYLVANIA.

WIND-BOX FOR GAS-PRODUCERS.

No. 908,479.

Specification of Letters Patent.

Patented Jan. 5, 1909.

Application filed March 23, 1908. Serial No. 422,623.

To all whom it may concern:

Be it known that I, WILLIAM R. MILLER, a citizen of the United States, residing at Pittsburg, in the county of Allegheny and State of Pennsylvania, have invented certain new and useful Improvements in Wind-Boxes for Gas-Producers, of which the following is a specification, reference being had therein to the accompanying drawing.

10 My invention refers to improvements in gas producers, more particularly to the class of water-seal gas producers, and relates to the wind box for supplying air to the fuel in combustion and to its construction and 15 mechanism for rotating it, whereby to disturb or agitate the fuel contents, during the air supply period.

In the operation of gas producers using bituminous or other fuel in a loose state, the 20 fuel charge is apt to become lodged or "bridged" within the producer walls, arresting the operation, and requiring the use of pokers from above to disturb the fuel and insure its continuous downward travel.

25 In carrying out my invention I employ a rotatable wind box, mounted within the producer upon a suitable support and provided with means for supplying air to the interior of the box at all positions in the manner 30 shown in the drawings and as hereinafter described.

Referring to the drawings, Figure 1 is a 35 partial sectional elevation of a producer illustrating the apparatus in cross section. Fig. 2 is a plan view, partially broken away, indicated by the line II. II. of Fig. 1. Figs. 3 and 4 are detail views illustrating a modified construction. Fig. 5 is a partial sectional elevation of a producer similar to Fig. 1, but 40 showing a modified construction. Fig. 6 is a plan view partially in section indicated by the line VI. VI. of Fig. 5.

The producer 2 as shown in the drawings is usually cylindrical in cross section, provided with the customary charging hopper having suitable feeding mechanism and a gas outlet, (not shown) at its upper portion.

3 is the water-seal basin, into which the ashes are deposited and from which they are 50 removed from time to time, the entire upper portion of the producer being supported above said basin by means of any suitable supporting structure as posts 4.

5 is the wind box consisting of a concentrically arranged hollow ring of any suitable

construction in cross section and preferably provided on its upper main body portion with outwardly and inwardly diverging sloping faces 6. 7. oppositely disposed and so arranged that the ashes, etc., will pass downwardly and to the outside and inside of the wind box respectively.

8 represents a supplemental similarly arranged coping annularly disposed upon the annular apex of the box 5, having similar outwardly and inwardly disposed sloping faces, while between the main box 5 and supplemental coping 8, are intervening inner and outer air outlet openings 9 arranged annularly around the structure, while similar series of air outlet openings 10 are arranged upon the inside and outside of the main wind box 5, for the purpose of providing a free distribution to the fuel.

The entire wind box, as thus constructed, 75 is rotatably mounted upon a central rotating hollow air supply post 11, rotatably set in the central portion of the basin 3 in any suitable manner to insure a water-tight joint. The lower portion of said hollow 80 post is provided with any convenient means for rotating it, as a worm wheel 12 and worm 13, the device being rotatably mounted upon a supporting base 14 of any suitable construction, with intervening rolling bearings 85 15 if desired, located within a suitable cavity 16 below the water basin. The hollow interior of post 11 is maintained in communication with an air and steam supply opening 17 leading to any source of pressure 90 as a pump or blower, and it will be understood that the connection therewith may be otherwise made to maintain constant connection with the blast. The upper end of the hollow post 11 is preferably tapered 95 toward a central point and of cone form as indicated at 18, so as to deflect the ashes downwardly and outwardly around the hollow post, while the wind box 5 is connected with the post by a series of hollow supporting arms 19, three of such arms being shown in the drawings.

For the purpose of facilitating rotation of the device and of avoiding the obstructing pressure of the fuel, arms 19 are preferably 105 made in diamond form in cross section or of any other suitable shape to more readily pass through the descending body of ashes.

For the purpose of providing means for disturbing the fuel immediately adjacent to 110

the wind box, it may be provided with projecting prongs or fingers *a* arranged upon the exterior or interior of the upper portion of the box, or both, and at any desired angle, 5 so that when the box is rotated, the said prongs will operate to dislodge any fixed or bridged fuel and insure its fall by gravity in the usual manner. Such construction is shown in Figs. 3 and 4.

- 10 In Figs. 5 and 6 I have shown a modified construction in which the wind box is rotatably mounted upon a circular supporting base 20, for which purpose the base of the wind box may be set upon said base within 15 inner and outer retaining flanges as shown, or mounted in any other suitable manner. The base 20 is supported upon suitably located standards 21 of any convenient construction, as hollow pipe, and for the purpose 20 of supplying air or air and steam to the interior of the wind box, one or more of said pipe supports 21 is connected by supply pipe 22 with a blower or any suitable air and steam supply device 23. The supply of air and 25 steam through said pipe and hollow standard to the wind box is under control so that the gas maker can force more or less air to the box, depending on the nature of the fuel or the condition of the gas required.
- 30 It will be understood that in such construction the base of the wind box is hollow and either continuously open throughout its cross area for the entire circumference, or crossed at intervals with bracing sections, 35 but so arranged that in whatever position the wind box may occupy on the supporting base 20, a continuous supply of air and steam may be distributed through standard 21' to its interior.
- 40 For the purpose of rotating the wind box, it is provided with an annular rack 24 at any convenient position, but preferably in its interior as shown, whereby such gearing is protected from the effect of the fuel in 45 combustion, and said rack 24 is engaged by the pinion 25 located at the upper end of shaft 26 extending through one of the hollow supports 21 and mounted in suitable journal bearings 27, 28. The shaft 26 is 50 provided with a bevel gear 29 into which meshes the driving pinion 30 of shaft 31 driven from any outside source of power, or power may be imparted to shaft 26 through other suitable or convenient means. It will 55 also be understood that any other mechanism may be employed for rotating the wind box.
- 60 The operation and advantages of the invention will be readily understood and appreciated by all those familiar with gas producer construction or operation inasmuch as it avoids the necessity of poking the fuel from above and insures regular even operation.
- 65 The construction of the device, the ar-

angement of the parts, or its various details may be changed or varied by the skilled mechanic, but all such changes or variations are to be considered as within the scope of the following claims.

70

What I claim is:—

1. In a gas producer, the combination with a source of air supply, of a horizontally rotatable open-center wind box having laterally arranged outlet openings, and means 75 for rotating the wind box.

2. The combination with a gas producer, of hollow supporting means in communication with a source of fluid supply, a hollow circular open-center wind box having laterally arranged outlet openings rotatably mounted on said supporting means and communicating therewith, and means for 80 rotating the wind box.

3. In a gas producer, the combination 85 with a source of air supply, of a horizontally rotatable open-center wind box having laterally arranged outlet openings and outer and inner downwardly diverging sloping walls, and means for rotating the wind box.

4. In a gas producer, the combination with a source of air supply, of a horizontally rotatable open-center wind box having laterally arranged outlet openings, outer and inner downwardly diverging sloping walls, 95 and an upper coping, and means for rotating the wind box.

5. In a gas producer, the combination 100 with a source of air supply, of a centrally arranged hollow rotatable post communicating therewith and provided with an open-center wind box communicating with the interior of the hollow post, and means for rotating the hollow post.

6. In a gas producer, the combination 105 with a source of air supply, of a centrally arranged hollow rotatable post communicating therewith and provided with a wind box connected with the hollow post by hollow arms, and means for rotating the hollow post.

7. The combination with a rotatable hollow post, of a hollow wind box and hollow supporting arms having an angular cross section for the purpose set forth, and means 115 for rotating the hollow post.

8. The combination with a rotatable hollow post having a coniform top, of a hollow wind box, hollow supporting arms, and means for rotating the hollow post.

9. In a gas producer, the combination with a source of air-supply, of a centrally arranged hollow rotatable post communicating therewith, a hollow circular wind box surrounding the upper portion of said post, 125 hollow supporting arms communicating with the hollow post and with the wind box, and means for rotating the hollow post, substantially as set forth.

10. A circular rotatable open-center wind 130

box having laterally arranged outlet openings and projecting prongs, and means for rotating the wind box, substantially as set forth.

- 5 11. In a gas producer, the combination with a centrally arranged hollow rotatable support and means for rotating it, of a superimposed open center wind box communicating with said support.

- 0 12. In a gas producer, the combination

with a centrally arranged hollow rotatable support and means for rotating it located at its base, of a superimposed open center wind box communicating with said support.

In testimony whereof I affix my signature 15 in presence of two witnesses.

WILLIAM R. MILLER.
